EDGE GRINDING MACHINE

Joseph P. Crowley, Toledo, Ohio, assignor to
 Libbey-Owens-Ford Glass Company, Toledo,
 Ohio, a corporation of Ohio

Application June 6, 1934, Serial No. 729,280

20 Claims. (Cl. 51—96)

The present invention relates broadly to improvements in grinding machines generally and more particularly to a machine for rounding and/or finishing the edges of sheets or plates of glass and the like.

An important object of this invention resides in the provision of a grinding machine of simplified and inexpensive construction primarily designed for use in grinding the curved edges of sheets or plates of glass which are to be employed as door or window lights in automotive vehicles, although it is of course in no way restricted to such use.

Another object of the invention is the provision of such a grinding machine of the above character which will round and finish the curved edges of the glass sheets or plates rapidly, accurately, and economically, and with a minimum effort and attention on the part of the operator whereby uniformly rounded edges with well finished surfaces may be secured.

Another object of the invention is the provision of such a grinding machine of the above character capable of grinding curved edges of different contours readily and conveniently and also so constructed that curved edges of different lengths may be ground with facility and accuracy.

A further object of the invention is the provision of such a grinding machine of the above character embodying a rotary grinding wheel, means mounted above said wheel for supporting a plurality of glass sheets to be ground, and means for rocking said supporting means to move the glass sheets backward and forward with the curved edges thereof to be ground over and in engagement with the grinding wheel, together with means for controlling and regulating the degree of rocking movement of the sheet supporting means, depending upon the length of arc or edge contour to be ground.

A still further object of the invention is the provision of such a grinding machine of the above character wherein the sheet supporting means is mounted above the grinding wheel in such a manner that it is capable of free vertical floating movement during the rocking thereof and depending upon the curvature of the edges being ground, means being also provided for varying the pressure of the glass sheets upon the said grinding wheel.

Still another object of the invention is the provision of such a grinding machine of the above character embodying novel means for supporting the glass sheets above the grinding wheel and which includes means engaging the edges of

the sheets to be ground to assist in properly positioning the said sheets preparatory to grinding, together with means for moving the said last-mentioned means away from the sheet edges to permit the grinding thereof upon rocking movement of the sheet supporting means in one direction, said edge engaging means being subsequently automatically returned to sheet engaging position upon rocking of the sheet supporting means in the opposite direction.

Other objects and advantages of the invention will become more apparent during the course of the following description when taken in connection with the accompanying drawings.

In the drawings wherein like numerals are employed to designate like parts throughout the same,

Fig. 1 is a side elevation of a grinding machine constructed in accordance with the present invention,

Fig. 2 is a vertical section therethrough taken substantially on line 2—2 of Fig. 1,

Fig. 3 is a perspective view of the upper portion of the machine showing particularly the means for supporting the glass sheets,

Fig. 4 is a detail plan view of a portion of the means for supporting the glass sheets,

Fig. 5 is a detail plan view of another portion of the sheet supporting means,

Fig. 6 is a transverse section taken substantially on line 6—6 of Fig. 2,

Fig. 7 is a detail elevation of the control switch,

Fig. 8 is a section taken substantially on line 8—8 of Fig. 1,

Fig. 9 is a section taken substantially on line 9—9 of Fig. 1, and

Figs. 10, 11, and 12 are side views of the upper portion of the machine showing different positions assumed by the sheet supporting means and glass sheets during the grinding operation.

The grinding machine herein provided is adapted to produce what is termed in the art as a "pencil edge" upon the glass sheets. The term "pencil edge" is used to designate an edge which is rounded transversely of the sheet to remove all sharp or square corners.

Referring now to the drawings and particularly to Fig. 2, the grinding machine includes a base 15 which is adapted to support the rotary grinding wheel 16 and the motor 17 for driving the same, said motor being mounted upon the top of said base and the grinding wheel being arranged to one side thereof.

The grinding wheel 16 is keyed to one end of 55

a horizontal shaft 18 and is provided in its periphery with a plurality of grooves 19 within which the edges of the glass sheets or plates to be ground are adapted to be received, as will be more clearly 5 hereinafter apparent. The shaft 18 is rotatably supported in the spaced bearings 20 and 21 carried by the base 15, said shaft projecting rearwardly beyond said base and journaled at its outer end in a bearing 22 carried by a gear case 23 suitably secured to the base 15. Keyed to 10 the shaft 18 within gear case 23 is a relatively large gear 24 meshing with a relatively smaller gear 25 fixed to the shaft 26 of motor 17, said shaft being preferably journaled in a bearing 27 also 15 carried by gear case 23. Upon operation of the motor 17, it will be readily apparent that the shaft 18 will be driven through the intermeshing gears 24 and 25 to effect the positive rotation of the grinding wheel.

20 Arranged at the front of the base 15 is a receptacle 28 within which the grinding wheel 16 is received, said receptacle being adapted to contain a suitable abrasive material within which the lower portion of the said wheel is adapted to be 25 immersed in a manner well known in the art. The top of the receptacle 28 is provided with a slot 29 through which the upper portion of the a grinding wheel projects. The receptacle is also 30 preferably provided with a door 30 to permit access thereto and with a drain outlet 31 at one corner thereof.

35 The base 15 is slidably associated with the receptacle 28 so that it can be moved vertically relative thereto to either raise or lower the grinding wheel. To this end, the rear vertical wall 32 of the receptacle is formed with a vertical undercut channel or way 33 (Fig. 6) within which the slide 34 formed on or carried by the base 15 is received. The rear wall of said receptacle is also 40 provided with a vertical slot 35 through which projects the annular portion 36 of the base 15 within which bearing 20 is mounted.

45 The base 15 is supported upon a screw 37 threaded at its lower end within a vertical cylinder or sleeve 38 carried upon the base portion 39 of the receptacle 28. The base 15 is formed with a recess 40 and keyed to the upper end of screw 37 within said recess is a relatively large gear 41 meshing with a relatively smaller gear 42 keyed to 50 the lower end of a vertical shaft 43 which passes downwardly through the said base. Extending transversely through the upper end of the shaft 43 is a rod 44, constituting a handle which may 55 be grasped by the operator to facilitate the turning of shaft 43. From the above, it will be seen that when it is desired to either raise or lower the base 15 and consequently the grinding wheel 16, it is simply necessary for the operator to grasp 60 the handle 44 and turn the shaft 43 in the desired direction. The rotation of gear 42 will serve to effect a corresponding rotation of gear 41 and upon rotation of gear 41, the screw 37 will be 65 threaded downwardly or upwardly within the sleeve 38 to effect either the raising or lowering of the base and grinding wheel.

70 The means for supporting the glass sheets to be treated comprises a box or holder designated in its entirety by the numeral 45, said holder being mounted above the grinding wheel 16 for free vertical and rocking movement as will be more 75 fully hereinafter described. The work holder 45 comprises a pair of spaced vertical side members 46 and 47 between which a plurality of glass sheets 48 to be ground are adapted to be received,

said sheets being disposed in a vertical position and the said side members being of such a size and so shaped that the curved edges 49 of the glass sheets to be treated project therebeyond as clearly illustrated in Figs. 1 and 10 to 12, so 5 that upon rocking of the work holder, the said edges will be moved backward and forward over and in engagement with the grinding wheel 16.

Arranged transversely between and carried by the side members 46 and 47 of work holder 45, 10 adjacent the upper ends thereof, are the three horizontally disposed rollers 50, 51 and 52, while positioned transversely between the said side members adjacent the lower ends thereof are the rollers 53 and 54, said rollers being adapted to 15 receive the glass sheets 48 to be ground therebetween and to maintain them in proper position during the grinding operation as will be more fully hereinafter described.

20 The roller 50 comprises, as best shown in Fig. 8, a horizontal bolt 55 having its inner end extending through a vertically disposed arcuate slot 56 formed in the side member 46 and being secured in fixed position by a nut 57 threaded thereupon outwardly of the said side member. 25 The opposite end of the bolt 55 is provided with a head 58. Mounted upon said bolt is a metal bushing 59 carrying a sleeve 60 preferably made of relatively soft rubber. This sleeve is formed with a plurality of uniformly spaced annular flanges 61 which define therebetween a plurality of grooves 62 within which the adjacent edges of the glass sheets 48 are adapted to be received.

30 The roller 51 is preferably of the same construction and arrangement as roller 50 with the exception that the supporting bolt 63 thereof projects at its opposite ends through spaced vertical slots 64 and 65 in the side members 46 and 47 respectively and has secured to each end 40 thereof outwardly of the adjacent side member a nut 66. Upon tightening of the nuts 66, the roller can be firmly secured in place. The roller 52 is preferably of the same construction as roller 51, with the supporting bolt 67 thereof projecting 45 at opposite ends through the aligned vertical slots 68 and 69 in the side members 46 and 47 respectively of the work holder and having threaded upon each end thereof a nut 70. Due to the particular manner of mounting the rollers 50, 51 50 and 52 as above described, it will be readily apparent that the said rollers may be adjusted independently of one another toward and away from rollers 53 and 54 to accommodate glass sheets of different sizes and shapes. 55

60 The rollers 53 and 54 are likewise of substantially the same construction as rollers 50, 51, and 52, with the exception that they are not adjustably mounted, the supporting bolts 71 and 72 respectively thereof simply passing through circular openings in the side members 46 and 47 of the work holder and having threaded upon opposite ends thereof nuts 73 and 74. The 65 grooves 62 in roller 50, as well as the corresponding grooves in rollers 51, 52, 53, and 54 are all in registry with the grooves 19 in grinding wheel 16.

70 Also positioned between and carried by the side members 46 and 47 of the work holder, adjacent the lower end thereof, is a substantially horizontal rectangular plate member 75 (Fig. 5) secured in place by a plurality of fastening elements 76. This plate member is disposed in substantial alignment with the rollers 53 and 54 and includes a relatively soft rubber pad 77 having a series 75

of spaced parallel grooves 78 formed therein, said grooves being in registry with the grooves in the rollers 53 and 54 and being adapted to receive the adjacent edges of the glass sheets 48 there-in. The plate member 75 also serves to hold the lower ends of the side members of the work holder in properly spaced relation. To assist in maintaining the upper end portions of the side members properly spaced from one another, there may be provided a bolt 79 (Fig. 3) passing through the said side members and having a nut 80 threaded upon each end thereof, a sleeve 81 encircling the bolt between the side members and acting to properly space the same.

It will be noted upon reference to Figs. 1 and 10 to 12 that when the glass sheets 48 are properly positioned within the work holder, the curved edges 49 thereof to be ground extend considerably beyond the side members thereof. In order to assist in steadyng the sheets during grinding, there may be provided an additional roller 82 adapted to rest upon the upper edges of the glass sheets and being also provided with a plurality of grooves within which the edges of the said sheets are received. As here shown, the roller is rotatably carried at its opposite ends by arms 83 and 84 mounted at their inner ends upon the supporting bolt 67 of the roller 52.

Suitably secured to the outer surfaces of the side members 46 and 47 of the work holder are the angular plates 85 and 86 respectively, to which are pivotally connected the inner ends of a pair of substantially horizontal, parallel supporting arms 87 and 88 respectively, said arms being also freely mounted intermediate their ends upon a horizontal shaft 89 passing transversely through a block 90 supported upon the top of the receptacle 28. The outer ends of the supporting arms 87 and 88 are bent inwardly as at 87' and 88' respectively, and suspended therefrom are a plurality of weights 91, said weights being hung upon an eye-bolt 92 attached at its upper end to the supporting arms by a transverse pin or the like 93. The weights 91 are provided to counter-balance the work holder 45 so that the glass sheets being ground rest more or less freely upon the grinding wheel. However, by varying the weights, the pressure of the glass sheets upon the grinding wheel may be increased or decreased as desired.

Fixed upon the shaft 89 at one end thereof, inwardly of supporting arm 87, is a bell crank lever 94 comprising the two angularly disposed portions or legs 95 and 96. Pivoted to the outer end of leg 95 of the bell crank lever is one end of a substantially horizontal connecting rod 97 pivotally connected at its inner end to the plate 85 adjacent the lower end thereof beneath supporting arm 87. Keyed to the opposite end of shaft 89, inwardly of supporting arm 88, is a lever 98, and pivotally connected thereto is one end of a substantially horizontal connecting rod 99 extending parallel with rod 97 and being pivotally connected at its inner end to the plate 86 beneath supporting arm 88.

Each of the supporting arms 87 and 88 is pivotally mounted at its inner end upon a horizontal pin 100 carried by the respective side member 46 or 47, while each of the connecting rods 97 and 99 is pivotally mounted at its inner end upon a horizontal pin 101. The opposed pins 100 are in horizontal alignment with one another and constitute the horizontal axis about which the work holder 45 is adapted to rock. The opposed pins

101 are also in horizontal alignment with one another.

Pivoted to the outer end of the leg 96 of bell crank lever 94 is the upper end of a substantially vertical pitman 102 pivotally connected at its lower end to a crank 103 keyed to a horizontal shaft 104, said shaft being driven from a motor 105 through a suitable chain and sprocket drive 106 and reduction gearing located in the housing 107. Upon rotation of the shaft 104, the pitman 102 will be given a substantially vertical upward and downward motion to effect the turning of the horizontal shaft 89 first in one direction and then the other to impart a substantially horizontal forward and backward motion to the connecting rods 97 and 99, it being of course understood that these rods work in unison. The reciprocation of the connecting rods will cause the work holder 45 to be rocked upon the pins 100, thereby causing the glass sheets 48 to be moved backward and forward with the curved edges 49 thereof to be ground over and in engagement with the grinding wheel. The pitman 102 preferably consists of a pair of aligned rods 108 and 109 screw threaded at their inner adjacent ends and connected together by a turn-buckle 110.

In the operation of the machine described above and when it is desired to grind the curved edges 49 of a plurality of sheets of glass 48, the work holder 45 is first moved to the position illustrated in Figs. 1 and 10, at which time the pitman 102 is at substantially the extreme limit of its upward movement while the connecting rods 97 and 99 are in retracted position. The glass sheets to be ground are then inserted horizontally into the outer open end of the work holder between the upper rollers 50, 51, 52, and 82 and the lower rollers 53 and 54, the upper edges *a* of the said sheets being received within the grooves in the said rollers 50, 51, 52, and 82, while the bottom edges *b* thereof are received within the grooves in rollers 53 and 54 and likewise within the grooves 78 formed in the rubber pad 77 carried by plate member 75.

When so positioning the glass sheets for grinding, it is of course desirable that some means be provided for limiting the inward movement of the said sheets when they are inserted within the work holder and for also lining up the curved edges 49 of the several sheets to be ground. For this purpose, there is provided a horizontal metal roller 111 carried by the work holder and against which the inner edges of the glass sheets are adapted to abut, said roller extending transversely of the said work holder and being supported at its opposite ends upon rods 112 and 113, each of said rods being slidably received within a sleeve 114 pivotally mounted at its inner end upon a pin 115 (Fig. 3) carried by the work holder. The rods 112 and 113 are slidably associated with the sleeves 114 so that the roller 111 can be moved inwardly or outwardly to accommodate glass sheets of different shapes and sizes, each rod being secured within its respective sleeve by a set screw 116.

Also carried by each of the side members 46 and 47 of work holder 45 is an angle plate 117 having a horizontal portion adapted to support the respective sleeve 114 and to in this manner limit the downward movement of the roller. It is preferred that the metal roller 111 be covered with a rubber sleeve 118 which is adapted to engage the edges of the glass sheets. In positioning the glass sheets within the work holder, therefore, the said sheets are moved inwardly until

the edges 49 thereof to be ground abut the roller 111, it being of course understood that the roller has first been adjusted to the desired position.

In order to facilitate the adjustment of the 5 roller 50 within the arcuate slot 56, there may be carried by the supporting bolt 55 thereof an arm 119 pivoted upon the pin 115 inwardly of side member 46 (Fig. 5). The nut 57 can also be formed with a handle 120. By turning the handle 10 120 to loosen nut 57, the supporting bolt 55 can be moved upwardly or downwardly within the arcuate slot 56, being swung about the axis of pin 115. When the roller has been moved to the desired position, it can be secured in such position by simply turning the handle 120 to tighten the nut 57.

After the glass sheets have been properly positioned, the motor 105 is placed in operation to rotate the shaft 104 and draw the pitman 102 downwardly, this movement of the pitman causing the shaft 89 to be rocked in a counterclockwise direction and imparting a forward horizontal movement to the connecting rods 97 and 99. This forward movement of the connecting rods 25 will cause the work holder 45 to be also rocked in a counterclockwise direction upon the pins 100 and during the turning of the said work holder, the curved edges 49 of the glass sheets 48 will of course be moved over and in engagement with 30 the grinding wheel 16, being received within the grooves 19 thereof. The grinding wheel is being simultaneously driven, preferably though not necessarily, in the opposite direction. The work holder may be turned approximately 90 degrees 35 and at the limit of its backward movement will assume substantially the position illustrated in Fig. 12. Thus, the curved edges 49 of the glass sheets may be ground from substantially the point c on edge b to the corner d.

40 Upon rocking of the work holder 45 in a counterclockwise direction and especially when it is desired to grind the edges 49 of the glass sheets to the corner d or, in fact, to any point above the normal position of the roller 111, it becomes 45 necessary that some means be provided for moving the said roller away from or out of engagement with the sheet edges. To accomplish this, there may be carried upon the top of the receptacle 28, at opposite sides of the grinding wheel 50 16, the vertical plates 121 and 122 adapted to be engaged by the roller 111 upon rocking movement of the work holder in a counterclockwise direction to move the said roller out of engagement with the sheet edges to permit the grinding 55 thereof. Thus, when the work holder reaches the position illustrated in Fig. 12, the roller 111 is entirely out of engagement with the glass sheets so that the said sheets are supported entirely upon the grinding wheel. The roller 111 60 may be provided adjacent its opposite ends with collars 123 and 124 which are adapted to engage the inclined edges 125 and 126 of the plates 121 and 122 respectively.

When the work holder has been moved to the 65 position illustrated in Fig. 12, the crank 103 has completed approximately one-half a revolution so that upon continued turning of the said crank, the pitman 102 will be started upwardly, thereby causing the shaft 89 to be rocked in a clockwise 70 direction to effect backward movement of the connecting rods 97 and 99. This movement of the connecting rods will in turn cause the work holder 45 to be rocked upon the pins 100 in a clockwise direction to return it to its starting position 75 shown in Figs. 1, 3, and 10. As the work holder is

rocked in a clockwise direction to return it to starting position, the roller 111 will be automatically caused to return to its normal position in engagement with the edges 49 of the glass sheets, the return movement of the said roller being 5 limited by the plates 117 engageable by sleeves 114.

It will of course be readily apparent that upon rocking of the work holder 45, the said holder will be permitted to simultaneously move freely vertically, depending upon the curvature of the sheet 10 edges being ground. This is due to the fact that the supporting arms 87 and 88 are freely mounted upon shaft 89. The pins 100 may therefore be said to constitute a floating axis upon which the work holder may be rocked. The machine herein 15 provided is therefore capable of grinding glass sheets of various sizes and shapes rapidly, accurately, and economically and with a minimum effort and attention on the part of the operator.

As pointed out above, it is preferable that the 20 weights 91 be such as to just counterbalance the work holder 45 so that the only pressure exerted upon the sheet edges being ground will be the weight of the sheets themselves. However, by removing some of the weights so that they are not 25 sufficient to counterbalance the holder 45, the pressure upon the sheet edges being ground will be increased whereas by adding additional weights, the pressure upon the sheet edges can be reduced.

It is desirable in the operation of the machine 30 to effect a slight raising of the glass sheets at the completion of the grinding operation to lift the said sheets out of contact with the grinding wheel in order to prevent "burning" of the edges being 35 ground. To this end, there is carried by the work holder 45 a pair of freely rotatable rollers 127 and 128 mounted upon the opposite ends of a bolt 129 passing transversely through the side members 46 and 47 and secured in place by nuts 130. These rollers are arranged outwardly of the said 40 side members and are of such diameter that they project slightly beneath the bottom edges thereof. Carried upon the top of the receptacle 28, adjacent one end thereof, for cooperation with the rollers 127 and 128, are the spaced blocks 131 and 132. 45

Upon the return of the work holder 45 to its starting position, the rollers 127 and 128 engaging blocks 131 and 132 will effect a slight tilting or raising of the said holder sufficient to lift the edges of the glass sheets out of contact with the grinding wheel as illustrated in Figs. 1 and 10. Upon loading of the work holder preparatory to the grinding operation, the said holder is also adapted to be in this position so that the curved edges 49 of the glass sheets will not contact with the grinding wheel as the said sheets are being placed in position. When the motor 105 is subsequently placed in operation to rock the work holder, the curved edges of the glass sheets will be gradually lowered to engage the grinding wheel as illustrated in Fig. 11.

Ordinarily, it will be found that one backward and forward rocking movement of the work holder will be sufficient to effect the desired grinding of the glass sheets. Therefore the present invention further contemplates the provision of means for automatically shutting off the motor 105 to stop the rocking movement of the work holder at the completion of the grinding operation. Thus, there is carried by the receptacle 28 70 a limit switch 133 connected in circuit with and adapted to control the operation of motor 105, said switch being provided with a control arm 134 to which is pivoted, as at 135, a lever 136. Carried at the upper end of this lever is a roller 137, 75

while the lower end thereof is notched as at 138 to provide a hand grip for the operator.

Secured to the side member 46 of work holder 45 for cooperation with the switch 133 is a trip member 139 (Figs. 1, 2, and 7). In operation, after the work holder has been rocked in a counterclockwise direction and then returned to its starting position to complete the grinding cycle, the trip member 139 engaging the roller 137 will force the control arm 134 downwardly to open the switch 133, thereby breaking the circuit through the motor 105 and stopping the movement of the work holder. The trip member, however, is not adapted to actuate the switch until after the rollers 127 and 128, engaging blocks 131 and 132, have caused the glass sheets to be lifted out of contact with the grinding wheel.

When it is desired to again place the machine in operation, it is simply necessary for the operator to swing the lever 136 about its pivot 135 to the position indicated by the broken lines in Fig. 7. This swinging movement of the lever will permit the control arm 134, which is of the spring-pressed type, to be automatically moved upwardly 25 to again close the switch and start the motor 105.

As pointed out above, with the machine operating as illustrated in the drawings, the edges of the glass sheets can be ground from substantially the point *c* to the corner *d*. However, it 30 may not always be desirable to grind this particular length of edge contour and therefore means is herein provided for regulating the length of arc or edge contour to be ground. For this purpose, the crank 103 is made adjustable 35 to increase or decrease the degree of rocking movement of the work holder. Thus, as shown particularly in Figs. 1 and 9, the crank is formed with a slot or guideway 140 within which is received the bearing block 141 carrying a horizontal pin 142 to which the lower end of the pitman 102 is suitably connected. The bearing block 141 is threadedly mounted upon a screw 143 passing loosely through the end plate 144 of the crank, said screw being provided with annular flanges 40 or washers 145 at opposite sides of the plate 144 so that it has rotatable but non-slidable movement. The screw 143 is also provided with a head 146 which may be engaged by a wrench or some other tool to effect the turning thereof. 45 By rotating the screw 143, the bearing block 141 can be threaded inwardly or outwardly thereupon as desired to increase or decrease the throw of the crank and in consequence the rocking movement of the work holder.

The pitman 102 is made adjustable so that it 50 is possible to grind up to the corner *d* of the glass sheets without excessive chamfer. In other words, by adjusting the length of the pitman, which can be effected by proper rotation of the 55 turnbuckle 110, it is possible to control the point at which the grinding of the sheet edges stops.

While the machine has been referred to above 60 as a grinding machine and also while it is primarily designed for this purpose, yet it may be readily adapted for polishing the curved edges of the glass sheets by the substitution of a suitable polishing wheel for the grinding wheel 16.

It is to be understood that the form of the invention herewith shown and described is to be 65 taken as the preferred embodiment of the same, and that various changes in the shape, size and arrangement of parts may be resorted to without departing from the spirit of the invention or the 70 scope of the subjoined claims.

I claim:

1. In a machine for grinding the curved edges of a glass sheet or plate, a rotary grinding wheel positioned to rotate about a substantially horizontal axis, means mounted above said wheel for supporting the glass sheet to be ground on edge in a substantially vertical position, means for rocking said supporting means to move the curved edge of the sheet to be ground over and in engagement with said grinding wheel, means engaging the edge of the sheet to be ground to assist in properly positioning the said sheet for grinding, and means for moving said last-mentioned means away from said edge to permit the grinding thereof upon rocking of the sheet supporting means. 15

2. In a machine for grinding the curved edges of a glass sheet or plate, a rotary grinding wheel positioned to rotate about a substantially horizontal axis, means mounted above said wheel for supporting the glass sheet to be ground on edge in a substantially vertical position, means for rocking said supporting means to move the curved edge of the sheet to be ground over and in engagement with said grinding wheel, and pivotally 20 mounted means engaging the edge of the sheet to be ground to assist in properly positioning the said sheet for grinding, said last-mentioned means being automatically movable away from said edge to permit the grinding thereof upon 25 rocking of the sheet supporting means.

3. In a machine for grinding the curved edges of a glass sheet or plate, a rotary grinding wheel positioned to rotate about a substantially horizontal axis, means mounted above said wheel for supporting the glass sheet to be ground on edge in a substantially vertical position, means for rocking said supporting means to move the curved edge of the sheet to be ground over and in engagement with said grinding wheel, pivotally 35 mounted means engaging the edge of the sheet to be ground to assist in properly positioning the said sheet for grinding, and means disposed in the path of said last-mentioned means for moving the same away from said edge to permit the 40 grinding thereof upon rocking of the sheet supporting means. 45

4. In a machine for grinding the curved edge of a glass sheet or plate, a rotary grinding wheel positioned to rotate about a substantially horizontal axis, a work holder above said wheel for supporting the glass sheet to be ground on edge in a substantially vertical position, means for rocking said work holder to move the curved edge of the sheet to be ground over and in engagement with said grinding wheel, means carried by the work holder and engaging the edge of the sheet to be ground, and means for moving said last-mentioned means away from said edge 50 to permit the grinding thereof upon rocking of the work holder. 55

5. In a machine for grinding the curved edge of a glass sheet or plate, a rotary grinding wheel positioned to rotate about a substantially horizontal axis, a work holder above said wheel for supporting the glass sheet to be ground on edge in a substantially vertical position, means for rocking said work holder to move the curved edge of the sheet to be ground over and in engagement with said grinding wheel, and pivotally 65 mounted means carried by the work holder and engaging the edge of the sheet to be ground, said last-mentioned means being automatically 70

movable away from said edge to permit the grinding thereof upon rocking of the work holder.

6. In a machine for grinding the curved edge of a glass sheet or plate, a rotary grinding wheel positioned to rotate about a substantially horizontal axis, a work holder above said wheel for supporting the glass sheet to be ground on edge in a substantially vertical position, means for rocking said work holder to move the curved edge of the sheet to be ground over and in engagement with said grinding wheel, pivotally mounted means carried by the work holder and engaging the edge of the sheet to be ground, and means disposed in the path of said last-mentioned means for moving the same away from said edge to permit the grinding thereof upon rocking of the work holder.

7. In a machine for grinding the curved edge of a glass sheet or plate, a rotary grinding wheel positioned to rotate about a substantially horizontal axis, a work holder above said wheel for supporting the glass sheet to be ground on edge in a substantially vertical position, means for rocking said work holder to move the curved edge of the sheet to be ground over and in engagement with said grinding wheel, pivotally mounted means carried by the work holder and engaging the edge of the sheet to be ground, and means for moving said last-mentioned means away from said edge to permit the grinding thereof upon rocking of the work holder in one direction, said pivotally mounted means being automatically returned to sheet edge engaging position upon rocking of the said work holder in the opposite direction.

8. In a machine for grinding the curved edge of a glass sheet or plate, a rotary grinding wheel positioned to rotate about a substantially horizontal axis, a work holder above said wheel for supporting the glass sheet to be ground on edge in a substantially vertical position, means for rocking said work holder to move the curved edge of the sheet to be ground over and in engagement with said grinding wheel, pivotally mounted means carried by the work holder and engaging the edge of the sheet to be ground, and means disposed in the path of said last-mentioned means for moving the same away from said edge to permit the grinding thereof upon rocking of the work holder in one direction, said pivotally mounted means being automatically returned to sheet edge engaging position upon rocking of the work holder in the opposite direction, and means carried by the said work holder for supporting the pivotally mounted means and for limiting movement thereof in one direction.

9. In a machine for grinding the curved edge of a glass sheet or plate, a rotary grinding wheel positioned to rotate about a substantially horizontal axis, means arranged above said wheel for supporting the glass sheet to be ground on edge in a substantially vertical position, means for rocking said supporting means to move the curved edge of the sheet to be ground over and in engagement with said grinding wheel, means for pivotally mounting the supporting means upon a floating axis so that it is capable of free vertical floating movement during the rocking thereof, means carried by said supporting means and engaging the edge of the sheet to be ground, and means for moving said last-mentioned means away from said edge to permit the grinding thereof upon rocking of the said sheet supporting means.

10. In a machine for grinding the curved edge

of a glass sheet or plate, a rotary grinding wheel positioned to rotate about a substantially horizontal axis, a work holder arranged above said wheel for supporting the glass sheet to be ground on edge in a substantially vertical position, means for rocking said work holder to move the curved edge of the sheet to be ground over and in engagement with said grinding wheel, means for pivotally mounting the work holder upon a floating axis so that it is capable of free vertical floating movement during the rocking thereof, pivotally mounted means carried by the work holder and engaging the edge of the sheet to be ground, and means for automatically moving said last-mentioned means away from said edge to permit the grinding thereof upon rocking of the work holder.

11. In a machine for grinding the curved edge of a glass sheet or plate, a rotary grinding wheel positioned to rotate about a substantially horizontal axis, a work holder arranged above said wheel for supporting the glass sheet to be ground on edge in a substantially vertical position, means for rocking said work holder to move the curved edge of the sheet to be ground over and in engagement with said grinding wheel, means for pivotally mounting the work holder upon a floating axis so that it is capable of free vertical floating movement during the rocking thereof, pivotally mounted means carried by the work holder and engaging the edge of the sheet to be ground, and means disposed in the path of said last-mentioned means for moving the same away from said edge to permit the grinding thereof upon rocking of the work holder in one direction, said pivotally mounted means being automatically returned to sheet edge engaging position upon rocking of the work holder in the opposite direction.

12. In a machine for simultaneously grinding the curved edges of a plurality of glass sheets or plates, a rotary grinding wheel positioned to rotate about a substantially horizontal axis, means arranged above said wheel for supporting the glass sheets to be ground on edge in a substantially vertical position including spaced vertical side members between which said sheets are received and means carried by and arranged between said side members for maintaining the said sheets in position during grinding, means for rocking the supporting means to move the curved edges of the sheets to be ground back and forth over and in engagement with said grinding wheel, means carried by the side members of said sheet supporting means and engaging the edges of the sheets to be ground, and means for moving said last-mentioned means away from the sheet edges to permit the grinding thereof upon rocking of the sheet supporting means.

13. In a machine for simultaneously grinding the curved edges of a plurality of glass sheets or plates, a rotary grinding wheel positioned to rotate about a substantially horizontal axis, means arranged above said wheel for supporting the glass sheets to be ground on edge in a substantially vertical position including spaced vertical side members between which said sheets are received and means carried by and arranged between said side members for maintaining the said sheets in position during grinding, means for rocking the supporting means to move the curved edges of the sheets to be ground back and forth over and in engagement with said grinding wheel, means pivotally carried by the side members of said sheet supporting means and engaging the

edges of the sheets to be ground, and fixed means disposed in the path of said last-mentioned means for moving the same away from the sheet edges to permit the grinding thereof upon rocking of the 5 sheet supporting means.

14. In a machine for simultaneously grinding the curved edges of a plurality of glass sheets or plates, a rotary grinding wheel positioned to rotate about a substantially horizontal axis, means 10 arranged above said wheel for supporting the glass sheets to be ground on edge in a substantially vertical position including spaced vertical side members between which said sheets are received and means carried by and arranged between said 15 side members for maintaining the said sheets in position during grinding, means for rocking the supporting means to move the curved edges of the sheets to be ground back and forth over and in engagement with said grinding wheel, means piv- 20 otally carried by the side members of said sheet supporting means and engaging the edges of the sheets to be ground, fixed means disposed in the path of said last-mentioned means for moving the same away from the sheet edges to permit the 25 grinding thereof upon rocking of the sheet supporting means in one direction, said pivotally mounted means being automatically returned to sheet edge engaging position upon rocking of the said supporting means in the opposite direction.

15. In a machine for simultaneously grinding 30 the curved edges of a plurality of glass sheets or plates, a rotary grinding wheel positioned to rotate about a substantially horizontal axis, a work holder arranged above said wheel for supporting the glass sheets to be ground on edge in a sub- 35 substantially vertical position including spaced vertical side members between which said sheets are received and means carried by and arranged between said side members for maintaining the said sheets in position during grinding, means for 40 rocking said work holder to move the curved edges of the sheets to be ground back and forth over and in engagement with said grinding wheel, means for pivotally mounting the work holder upon a floating axis so that it is capable of free 45 vertical floating movement during the rocking thereof, means carried by the side members of said work holder and engaging the edges of the sheets to be ground to assist in the proper pos- 50 titioning of the said sheets for grinding, and means 55 for moving said last-mentioned means away from the sheet edges to permit the grinding thereof upon rocking of the sheet supporting means.

16. In a machine for simultaneously grinding the curved edges of a plurality of glass sheets or 60 plates, a rotary grinding wheel positioned to rotate about a substantially horizontal axis, a work holder arranged above said wheel for supporting the glass sheets to be ground on edge in a sub- 65 substantially vertical position including spaced vertical side members between which said sheets are received and means carried by and arranged between said side members for maintaining the said sheets in position during grinding, means for 70 rocking said work holder to move the curved edges of the sheets to be ground back and forth over and in engagement with said grinding wheel, means for pivotally mounting the work holder upon a floating axis so that it is capable of free 75 vertical floating movement during the rocking thereof, means pivotally carried by the side mem-

bers of the work holder and engaging the edges of the sheets to be ground, and fixed means disposed in the path of said last-mentioned means for moving the same away from the sheet edges to permit the grinding thereof upon rocking of the 5 work holder in one direction, said pivotally mounted means being automatically returned to sheet edge engaging position upon rocking of the said work holder in the opposite direction.

17. In a machine for simultaneously grinding 10 the curved edges of a plurality of glass sheets or plates, a rotary grinding wheel positioned to rotate about a substantially horizontal axis, a work holder arranged above said wheel for supporting the glass sheets to be ground on edge 15 in a substantially vertical position including spaced vertical side members between which said sheets are received and means carried by and arranged between said side members for maintaining the said sheets in position during grinding, means for rocking said work holder to move the curved edges of the sheets to be ground back and forth over and in engagement with said 20 grinding wheel, a horizontally disposed roller engaging the edges of the glass sheets to be 25 ground, supporting means for the roller pivotally connected to the side members of the work holder, and means engaging said roller for moving the same out of engagement with the sheet edges to permit the grinding thereof upon rocking of 30 the work holder in one direction, said roller being automatically returned to sheet engaging position upon rocking of the said work holder in the opposite direction.

18. In a machine for simultaneously grinding 35 the curved edges of a plurality of glass sheets or plates, a rotary grinding wheel positioned to rotate about a substantially horizontal axis, a work holder arranged above said wheel for supporting the glass sheets to be ground on edge in 40 a substantially vertical position including spaced vertical side members between which said sheets are received and means carried by and arranged between said side members for maintaining the said sheets in position during grinding, means 45 for rocking said work holder to move the curved edges of the sheets to be ground back and forth over and in engagement with said grinding wheel, a horizontally disposed roller engaging the edges of the glass sheets to be ground, sup- 50 porting means for the roller pivotally connected to the side members of the work holder, fixed means disposed in the path of said roller for moving the same out of engagement with the sheet edges to permit the grinding thereof upon 55 rocking of the work holder in one direction, said roller being automatically returned to sheet en- 60 gaging position upon rocking of the said work holder in the opposite direction, and means carried by the work holder for supporting the roller and for limiting the return movement thereof.

19. In a machine for grinding the curved edge of a glass sheet or plate, a rotary grinding wheel positioned to rotate about a substantially horizontal axis, means mounted above said wheel for supporting the glass sheet to be ground on edge 65 in a substantially vertical position, an arm to which the supporting means is pivoted on a horizontal axis for rocking movement to carry the curved edge of the glass sheet over the grinding 70 wheel, a pivotal support for the arm at one side of the axis of rotation of the grinding wheel about which the arm swings freely during the grinding operation, movable means on the sheet supporting means maintained by gravity in holding en- 75

gagement with the curved edge of the sheet, stop means positioned so as to engage the movable means and disengage it from the glass sheet after the curved edge has been partially ground, and means for rocking said supporting means.

- 5 20. In a machine for grinding the curved edge of a glass sheet or plate, a rotary grinding wheel positioned to rotate about a substantially horizontal axis, means mounted above said wheel for supporting the glass sheet to be ground on edge in a substantially vertical position, an arm to which the supporting means is pivoted on a horizontal axis for rocking movement to carry the curved edge of the glass sheet over the grinding

wheel, a pivotal support for the arm at one side of the axis of rotation of the grinding wheel about which the arm swings freely during the grinding operation, a member mounted on the sheet supporting means for swinging movement toward the curved edge of the sheet yieldingly maintained in engagement therewith, stop means positioned so as to release said member from the edge of the sheet during the last part 5 of the rocking movement of the supporting means, and means for rocking said supporting means.

JOSEPH P. CROWLEY.
